[57] CLAIM

The ornamental design for a holder for cylindrical container, as shown and described.

DESCRIPTION

FIG. 1 is a side elevational view of a holder for cylindrical container showing my new design, the portion of a container being shown in broken lines for illustrative purposes only;

FIG. 2 is a top plan view thereof;

FIG. 3 is a front elevational view thereof;

FIG. 4 is a back elevational view thereof; and

FIG. 5 is a bottom plan view thereof.

Fig. 1.

Fig. 3.
